CHARLES E. ENNES AND CHARLES D. McDONALD, OF CHICAGO, ILLINOIS, ASSIGNEES
TO THE McDONALD MACHINE CO., OF CHICAGO, ILLINOIS, A CORPORATION OF
ILLINOIS.

METAL-SHEARING MACHINE.

1,194,728.

Specification of Letters Patent. Patented Aug. 15, 1916.

Application filed May 4, 1916. Serial No. 95,485.

To all whom it may concern:

Be it known that we, CHARLES E. ENNES and CHARLES D. McDONALD, both citizens of the United States, residing at Chicago, in the county of Cook and State of Illinois, have invented certain new and useful Improvements in Metal-Shearing Machines, of which the following is a specification.

The present invention relates to a machine for cutting up a blank of metal into a number of strips of accurate size and shape for feeding into an automatic die-press, thereby enabling the continuous operation of a plurality of presses from a single source of blank supply; and the basic principle of the machine is described in Letters Patent No. 1,110,810 granted to C. D. McDonald September 15, 1914, for metal shearing machine, and Letters Patent No. 1,174,747 granted March 7, 1916, to C. D. McDonald, for metal shearing machine.

One object of the invention is to provide means for giving the work an initial movement in the direction of the shearing mechanism and then imparting a secondary movement in the same direction for centering the work with respect to the shearing mechanism.

A further object of the invention is to produce a cut along the side of the work and to shift the work in accordance with this cut to center the work with respect to the shearing mechanism for subsequent side-trimming operations.

A further object of the invention is to provide means for allowing the side-trim to drop away from the body of the work at each side-trimming operation.

A further object of the invention is to arrange the various mechanisms whereby both movements of the work for centering purposes,—the placing of the cut which allows the side-trim to drop away from the main body of the work, and the severance of the waste ends from certain of the blanks—are regulated and operated by the movements of the cross-head of the shearing mechanism, thereby insuring a perfect timing of these mechanisms with respect to the shearing operation.

A further object of the invention is to

provide a plurality of blank receptacles all arranged to the rear end of the machine, thereby enabling the removing of blanks to the die-presses in a ready and quick manner. 55

A further object of the invention is to trim the irregular or imperfect end from certain of the blanks and to provide discharging means for forcing said imperfect end out from the shearing mechanism. 60

A further object of the invention is to provide members formed with an edge or point upon which the work lying to each side of the shearing mechanism rests, thereby insuring a ready discharge of the work resting on these members away from the shearing mechanism after the shearing operation. And the invention further consists in the features of construction and combination of parts hereinafter described 70 and claimed.

In the drawings: Figure 1 is a plan view of a machine embodying the mechanism of the present invention; Fig. 2, a vertical section showing the work advanced to the 75 limit of the first feeding movement for the purpose of receiving an edge-trimming cut; Fig. 3, a view similar to Fig. 2, showing the work advanced into the position assumed by the second movement of the feed bar; 80 Fig. 4, a view similar to Fig. 3, showing the work advanced by the centering means to position it against the fixed stop; Fig. 5, a section on line 5—5 of Fig. 1, looking in the direction of the arrow; Fig. 6, a detail 85 plan section of the shearing mechanism, showing the work being operated upon; Fig. 7, a detail section, looking at the rear of the shearing mechanism and showing the work in position; Fig. 8, a detail showing 90 the correlation between the feed bar and the means for giving the work the movement to center it with respect to the shearing mechanism; and Fig. 9, a section on line 9—9 of Fig. 8, looking in the direction 95 of the arrow.

As stated, the present invention relates to a machine which is adapted to receive sheets of work in the form of sheet metal and sever the same into a series of elongated 100 scroll-edge blanks, which are subsequently used in automatic die-presses for forming can

tops and similar articles. By the use of a machine of the character herein described, these blanks can be produced very rapidly and in great numbers, thereby enabling a continuous operation of a plurality of die-presses from this single source of blank supply, which is highly desirable, inasmuch as the continuous operation of the die-presses means an increased output therefrom and a consequent reduction in the cost of the article turned out by the presses.

Referring now to the drawings, the mechanism is mounted upon a standard or base 10, which supports a table 11 and a body 15 or holder 12 for the female portion of the shearing mechanism. Also carried by the standard is a frame 13, in which is slidably mounted a cross-head 14 that carries the male die of the shearing mechanism. Affixed to the upper surface of the table, and which for convenience of description will be termed the delivery end of the machine, is a diagonally-disposed guide rail 15 and a spring-pressed roller 16. It will be noted that the roller is lying approximately opposite from the inner end of the guide 15. This insures the work being turned into a straight line when entering the machine. This arrangement of guides and roller is fully shown and described in Patent No. 1,174,747 referred to above, and a detailed description will not be given in this case.

Running across the upper surface of the table and at the delivery end thereof, are companion chains 17, each of which is provided with a finger or fingers 18. These chains are driven from a cross-shaft 19 and through a suitable connection from the main drive shaft 20, this connection as shown 40 being in the form of a sprocket wheel 21 attached to the shaft 19, and a sprocket wheel 22 attached to a stub shaft 23, upon which stub shaft is mounted a gear 24 meshing with a gear 25 on the main drive shaft; 45 and a chain 26 forms the connection between the sprockets 22 and 21.

When the work has been delivered by the operation of the chains 17, it is in position to have its rear end engaged by the rear-most finger 27 of a reciprocating feed bar 28. This feed bar is actuated by a link 29 connected to a pivoted arm 30 driven by a link 31, which travels in a slot 32 in a disk 33 on the main drive shaft 20. The work 50 when engaged by this finger 27 is advanced to the position shown in Fig. 2, and after it has reached this position, the cross-head 14 descends and trims off the front edge of the blank. This is for the purpose of making the sheet of work a uniform length.

Attached to the cross-head 14 is a male cutting die 34 of the shearing mechanism, which also embodies a male cross cutting die 35, which coöperates with a female 60 cross cutting die 35^a for severing a waste

end off from the blank, as will be herein-after explained. Also carried by the cross-head and extending in a forward direction from the die 34 is a cutter 36, which operates to perform a side-trimming cut on the work. With the work in the position shown in Fig. 1, wherein it is in place to receive the edge-trimming and side-trimming cuts, the die 34, when it descends, will sever the front edge of the blank and also sever a portion of the side edge. This forms an offset or notch along the side edge, which establishes a line for subsequent side-trimming cuts, so that at the first operation of the press the work is trimmed both along the forward and side edges. After this has been accomplished, the work is then engaged by the second of the feed fingers of the feed bar 28, which finger is designated by the numeral 37, and is carried forward to the position shown in Fig. 3, which moves it beyond the female shearing die 38 and into proximity to a fixed plate or stop 39 lying to the rear or discharge end of the machine. After the finger has advanced the work into this position, it starts upon its backward movement. Then, as the die descends, a pin 40 carried in a bracket 41 engages with the walls of a cam slot 42 formed in a plate 43, and this plate is attached to a cross-bar 44, which connects two parallelly extending bars 45. These bars 45 are suspended above the surface of the table by means of bridge plates 46 forming slotted supports 47, in which the bars 45 travel.

The bars 45 have mounted thereon a plurality of plates 48 rendered adjustable by suitable slot and bolt connections 49, and each plate carries a pivoted finger 50 held normally downward by a spring 51. By referring to the drawings, it will be evident that as the work is passed beneath these fingers 50, they will lift upward to allow such passage. After the work has been forced by the fingers they will drop behind the work and into the position indicated in Figs. 2 and 3. As stated, the work is forced into the position shown in Fig. 3 by the forward movement of the feed bar, and when it reaches this position the feed bar starts back.

The rear edge of the work, as will be seen from the drawings, has been forced beyond the first of the fingers 50. These fingers will accordingly drop downward and behind the rear edge of the work, as will be understood from Fig. 3. Then the cross-head descending pushes the pins 40 down in the cam slot 42, which forces the plate 43, connecting bar 44, and parallel bars 45, and fingers 50, in a direction toward the shearing mechanism. This movement is a relatively short one and is sufficient to cause one of the fingers 50 to engage the rear edge of the work and move the forward edge of the

latter up into engagement with the stop 39. When so positioned, the work is spaced a proper distance beyond the shearing dies, and thus, when the shearing mechanism 5 acts, a blank of proper width is produced.

From the foregoing it will be seen that the work is first fed in the direction of the shearing mechanism by the feed bar, and then given a subsequent movement in the 10 same direction, to bring it up into position whereby it is centered with respect to the shearing mechanism to produce a blank of proper width. When so centered, the shearing dies act to sever that work lying to the 15 rear of the shears and also acts to sever the work lying between the shearing dies, producing two blanks at this operation.

In order to feed the work properly through the die-presses, all of the blanks 20 must be of uniform character, that is, each must terminate midway of one of the neck or reduced portions 52, which connect the enlarged portions 53. Therefore, it is necessary to sever the ends from that portion 25 of the work lying between the edges of the shearing die, and for this purpose the cross dies 35 and 35^a are provided, which cut off this surplus end and make each blank of a uniform character. And to eject this cut 30 end from the machine, spring-pressed ejector pins 35^b are provided; also ejectors 35^c are provided for the regular blank which is formed between the dies of the main shearing members.

35 As previously explained, a notch is formed at the time the edge-trimming operation is carried out. This notch provides a guide or line for subsequent side-trimming operations, which side-trim is necessary, owing to variances in the widths of the metal.

40 When the cross-head 14 descends, a cam or wedge 54 acts to engage the side of the work and shift it longitudinally of the shearing mechanism and against a fixed stop 45 55; that is, the inner edge of the notch formed by the initial side-trimming operation is forced against this stop. Thus, at each shearing operation the work is forced 50 into position, so that the blanks are cut to proper length. This side cut is shown and described in the foregoing-mentioned Patent 45 No. 1,174,747, granted March 7, 1916, to C. D. McDonald. The difference between that portion of the invention shown in said 55 patent and in the present application lies in the provision of the fixed wedge attached to the cross-head for forcing the work against the stop 55. There is also provided a punch 56 (see Fig. 5), which is actuated by a contact 57 carried by the cross-head. This 60 punch places a hole along the side edge of the work, whereby when the work is trimmed by the side-trimming cutter, it falls away therefrom. This feature is also 65 shown and described in the McDonald Pat-

ent No. 1,174,747 above referred to. It is to be noted, however, that in the present invention, the operation of the means which forces the work crosswise of the shearing mechanism to center it, the means which 70 forces the work longitudinally of the shearing mechanism to center it, the side-trimming die, the surplus end-trimming die, and the punch for making the holes in the side of the work, are all actuated directly by the 75 cross-head 14. As all of these operations must occur after the movement of the work by the feed bar and prior to the cutting stroke of the shearing dies, it is obvious that a perfect timing arises by moving all of 80 these parts through the operation of this cross-head, which, when it reaches a certain position, produces the shearing cut.

The work during the operation of the machine is positioned most of the time to 85 both sides of the shearing mechanism, and certain of the blanks are formed from that portion lying outside of the shearing mechanism. There must, of course, be a support upon each side of the shears during the 90 shearing operation, but this support should be of a nature so as to allow the severed work to easily and quickly drop away after the shearing operation. To accomplish this, I have provided strips 58, which are 95 beveled on their upper face so as to produce a point or edge 59 (see Fig. 7). Thus the work is given support, but when severed by the action of the shearing mechanism, quickly and easily falls away from the 100 shearing dies.

There is a blank formed from that portion of the work lying to the rear of the discharge end of the shearing dies, a blank 105 formed from that portion of the work lying between the shearing dies, and a blank formed from that portion of the work which is last placed to the front or delivery end of the shearing dies. It is necessary to provide receptacles for each one of these 110 blanks, and it is highly desirable that these receptacles all lie to the rear of the machine, where they are easily accessible. We therefore provide a receptacle 60, which receives the blanks formed by that portion of 115 the work placed to the rear of the shearing dies. The work when severed falls down an inclined plate 61 and into this receptacle. We also provide a receptacle 62 to receive the blanks formed by that portion of the 120 work lying between the shearing dies. These blanks are guided into this receptacle by a plate 63. This plate swings, whereby it is moved out of position when the initial trimming cut is made, to allow the trimmed 125 edge to fall outside of the receptacle 62. This trimmed edge travels along a guide plate 64. The operation of this swinging plate 63 is fully shown and described in Patent No. 1,174,747 above referred to. 130

4 There is further provided a receptacle 65 to receive the blanks formed by that portion of the work placed in front of the shearing dies; and a guide plate 66 is provided for 5 directing the work into this receptacle. Thus all of the blanks are deposited to the rear of the machine, where they can be easily and quickly removed by the attendant and conveyed to the various die-presses.

10 As first stated, the main object of these machines is to produce within a specified time a large quantity of blanks accurately trimmed and sized for feeding into automatic die-presses, and hence the requirement for the centering and trimming operations that have been heretofore described.

We claim:

1. In a machine of the class described, the combination of shearing mechanism, 20 means for feeding the work in a direction toward the shearing mechanism with an intermittent movement, and means for imparting additional movement to the work in the same direction as the feeding movement and at the end of each feeding movement to center the work with respect to the shearing mechanism, substantially as described.

2. In a machine of the class described, the combination of shearing mechanism, means for feeding the work in a direction toward the shearing mechanism with an intermittent movement, a stop member, and means for imparting additional movement to the work in the same direction as the feeding movement and at the end of each feeding movement to bring it against the stop member, whereby the work is centered with respect to the shearing mechanism, substantially as described.

3. In a machine of the class described, the combination of shearing mechanism, means for feeding the work in a direction toward the shearing mechanism with a step by step movement, each step comprising a long movement followed by a short movement and both in the same direction, means for imparting the long portion of the feeding step, means for imparting the short portion of the feeding step, said short movement 45 acting to center the work with respect to the shearing mechanism, substantially as described.

4. In a machine of the class described, the combination of shearing mechanism, reciprocating means for feeding the work in a direction toward the shearing mechanism with a step by step movement, and means for imparting an additional movement to the work in the same direction as the feeding movement and at the end of each feeding step to center the work with respect to the shearing mechanism, substantially as described.

5. In a machine of the class described, the combination of shearing mechanism, means

for feeding the work in a direction toward the shearing mechanism with an intermittent movement, and intermittently acting means for imparting an additional movement to the work in the same direction as the feeding movement and at the end of each feeding movement to center the work with respect to the shearing mechanism, substantially as described.

6. In a machine of the class described, the combination of shearing mechanism, reciprocating means for feeding the work in a direction toward the shearing mechanism in a step by step movement, and reciprocating means operating on the completion of each feeding movement to impart additional movement to the work in the same direction as the feeding movement and at the end of each feeding movement to center the work with respect to the shearing mechanism, substantially as described.

7. In a machine of the class described, the combination of shearing mechanism, means for feeding the work in a direction toward the shearing mechanism with a step by step movement, a stop member beyond the shears, each feeding step comprising two movements in the same direction, the first of said movements placing the edge of the work adjacent the stop member, the second movement bringing the edge of the work against the stop member to center the work with respect to the shearing mechanism, substantially as described.

8. In a machine of the class described, the combination of a fixed stop member beyond the shearing dies, means for feeding the work in a direction toward the shearing mechanism with a step by step movement, each of said movements carrying the work to a point adjacent the stop, and means for imparting additional movement to the work in the same direction as the feeding movement and at the end of each feeding movement to bring the work against the stop and center it with respect to the shearing mechanism, substantially as described.

9. In a machine of the class described, the combination of shearing mechanism, a table, means for feeding the work across the table in a direction toward the shearing mechanism, and means suspended above the table for imparting additional movement to the work in the same direction as the feeding movement to center the work with respect to the shearing mechanism, substantially as described.

10. In a machine of the class described, the combination of shearing mechanism, a table, means for feeding the work across the table with a step by step movement in a direction toward the shearing mechanism, and intermittently operated means suspended above the table for imparting additional movement to the work in the direction of

the feeding movement and at the end of each feeding movement to center the work with respect to the shearing mechanism, substantially as described.

- 5 11. In a machine of the class described, the combination of shearing mechanism, including a movable die, means for feeding the work in a direction toward the shearing mechanism, and means controlled by the 10 movement of said die for imparting additional movement to the work in the same direction as the feeding movement to center the work with respect to the shearing mechanism, substantially as described.
- 15 12. In a machine of the class described, the combination of shearing mechanism, including a movable die, feed means for moving the work in a direction toward the shearing mechanism with a step by step movement, means controlled by the movement of 20 said die for imparting an additional movement to the work in the same direction as the feeding movement and at the end of each feeding movement to center the work with respect to the shearing mechanism, substantially as described.

- 30 13. In a machine of the class described, the combination of shearing mechanism, including a movable die, means for feeding the work in a direction toward the shearing mechanism with a step by step movement, intermittently acting means controlled by the movements of the die for imparting additional movement to the work in the same 35 direction as the feeding movement and at the end of each feeding movement to center the work with respect to the shearing mechanism, substantially as described.

- 40 14. In a machine of the class described, the combination of shearing mechanism, including a movable die, a table, means for feeding the work across the table in a direction toward the shearing mechanism, and means suspended above the table and controlled by the movements of said die for imparting additional movement to the work in the same direction as the feeding movement to center the work with respect to the shearing mechanism, substantially as described.

- 45 15. In a machine of the class described, the combination of shearing mechanism, means for feeding the work in a direction toward the shearing mechanism with a step by step movement, a slidable bar, a member 50 on said bar adapted to engage with the work, and means for actuating said bar at the end of each feeding step to give additional movement to the work to center the work with respect to the shearing mechanism, substantially as described.

- 60 16. In a machine of the class described, the combination of shearing mechanism, means for feeding the work in a direction toward the shearing mechanism with a step by step movement, a fixed stop, a slidable

bar, a member on the bar for engaging the work, and means for actuating the bar at the end of each feeding movement to place the work against the stop to center it with respect to the shearing mechanism, substantially as described. 70

17. In a machine of the class described, the combination of shearing mechanism, means for feeding the work with a step by step movement toward the shearing mechanism, a bar suspended above the work, a mounting for the bar in which it slides, a member carried by the bar adapted to engage with the work, and means for actuating the bar at the end of each feeding movement 80 to give the work an additional movement to center the work with respect to the shearing mechanism, substantially as described.

18. In a machine of the class described, the combination of shearing mechanism, 85 means for feeding the work in a direction toward the shearing mechanism with a step by step movement, a bar suspended above the work, a finger carried by the bar and arranged to drop behind the rear edge of the work as the work is carried past the finger, and means for imparting a movement to the bar at the completion of each feeding movement, whereby said finger engages and moves the work in the same direction as the feeding movement to center the work with respect to the shearing mechanism, substantially as described. 90

19. In a machine of the class described, the combination of shearing mechanism, including a movable die, means for feeding the work with a step by step movement in a direction toward the shearing mechanism, a bar above the work, means controlled by the movement of the die for actuating said bar, 100 said bar operating at the end of each feeding movement, whereby an additional movement is given to the work to center it with respect to the shearing mechanism, substantially as described. 105

20. In a machine of the class described, the combination of shearing mechanism, including a movable die member, means for feeding the work in a direction toward the shearing mechanism with a step by step movement, a slidable bar, a member carried by the bar adapted to engage the work, and means controlled by the movement of said die for actuating the bar at the end of each feeding movement, whereby an additional movement is given to the work and the work centered with respect to the shearing mechanism, substantially as described. 115 120

21. In a machine of the class described, the combination of shearing mechanism, including a movable die, means for feeding the work with a step by step movement toward the shearing mechanism, means for imparting an additional movement to the work in the direction of the feeding movement and 125 130

at the completion of each feeding movement, and means for actuating said additional movement means, embodying a pin and cam connection between the movable die and said additional movement means, substantially as described.

22. In a machine of the class described, the combination of shearing mechanism, including a movable die, means for feeding the work in a direction toward the shearing mechanism with a step by step movement, a bar suspended above the work, a member on the bar adapted to engage the work, a member secured to the bar and formed with a cam slot, a pin carried by the movable die and in engagement with the cam slot, said pin acting to impart a movement to the bar at the end of each feeding movement, whereby an additional movement is given to the work in the same direction as the feeding movement to center the work with respect to the shearing mechanism, substantially as described.

23. In a machine of the class described, the combination of shearing mechanism, means for feeding the work in a direction toward the shearing mechanism with a step by step movement, a slideable bar, a member on said bar adapted to engage with the work, means for actuating said bar at the end of each feeding step to give additional movement to the work at the end of each feeding step whereby the work is centered with respect to the shearing mechanism, and means for adjusting the work-engaging member carried by the bar, substantially as described.

24. In a machine of the class described, the combination of shearing mechanism, means for feeding the work toward the shearing mechanism, a movable die member, a member carried by the movable die member having a cam face thereon, said face engaging the work to move it longitudinally of the shearing mechanism prior to the shearing operation for centering the work with respect to the shearing mechanism, substantially as described.

25. In a machine of the class described, the combination of shearing mechanism embodying a movable die member, means for feeding the work toward the shearing mechanism, and means controlled by the movement of said die member for shifting the work in two directions previous to the shearing operation for centering the work with respect to the shearing mechanism, substantially as described.

26. In a machine of the class described, the combination of shearing mechanism, means for feeding the work in a direction toward the shearing mechanism, a fixed stop beyond the shearing mechanism, a fixed stop to one side of the shearing mechanism, and means for moving the work into engagement with both of said stops previous to the shear-

ing operation for centering the work with respect to the shearing operation, substantially as described.

27. In a machine of the class described, the combination of shearing mechanism, embodying die members spaced apart a distance equal to the width of a to-be-cut blank, whereby a blank is formed by the work lying between said die members, said blank consisting of a series of enlarged portions alternating with reduced neck portions, a cross die extending between said spaced-apart dies and located midway of each of the outer neck portions of the blank, said cross dies acting to sever the surplus ends from each blank, whereby each end of the blank is made to terminate midway of the neck portion, and an ejector for forcing said cut surplus ends out from the die members, substantially as described.

28. In a machine of the class described, the combination of shearing mechanism, means for feeding the work across the shearing mechanism, a support upon each side of the shearing mechanism upon which the work rests, said supports each consisting of a member formed with a blade-like edge on which the work rests, substantially as described.

29. In a machine of the class described, the combination of shearing mechanism, means for feeding the work across the shearing mechanism, means for supporting the work upon each side of the shearing mechanism, consisting of members each beveled upon their upper face to provide a blade-like edge upon which the work rests, substantially as described.

30. In a machine of the class described, the combination of shearing mechanism, including a movable die member, means for feeding the work into position to be acted upon by the shearing mechanism, means for centering the work with respect to the shearing mechanism controlled by the movements of the die member, and a die for performing a side-trimming operation carried by the die member, substantially as described.

31. In a machine of the class described, the combination of shearing mechanism, including a movable die member, means for feeding the work into position to be acted upon by the shearing mechanism, means for centering the work with respect to the shearing mechanism controlled by the movements of the die member, a die for performing a side-trimming operation carried by the die member, and means actuated by the movement of the die member for placing a cut at intervals along the side of the work to allow that portion of the work cut by the side-trimmers to fall away from the main body of the work, substantially as described.

32. In a machine of the class described, the combination of shearing mechanism, in-

cluding a movable die, a side-trimming die carried by the movable die, means for feeding the work in a direction toward the shearing mechanism, and means controlled by the movement of the die for giving the work an additional movement in the direction of the feeding movement, and also a movement crosswise of the direction of said additional movement to center the work with respect to the shearing mechanism, substantially as described.

33. In a machine of the class described, the combination of shearing mechanism, comprising die members spaced apart from one another a distance equal to the width of a to-be-cut blank, means for positioning the work upon each side of the die members a distance equal to the width of a to-be-cut blank, a series of receptacles for receiving the blanks formed from the work lying be-

tween the die members and from that portion of the work extending beyond the die members, all of said receptacles being placed to the rear of the machine, and guides for conducting the blanks to the respective receptacles, substantially as described. 25

34. In a machine of the class described, the combination of shearing mechanism, including a movable die, a fixed stop to the rear of the shearing mechanism, a fixed stop 30 to the side of the shearing mechanism, a side-trimming die carried by the movable die, and means controlled by the movements of said die for moving the work in two directions to bring it against both of said 35 stops, whereby the work is centered with respect to the shearing mechanism, substantially as described.
